(57) **CLAIM**

The ornamental design for a paw print accessory, as shown and described.

DESCRIPTION

FIG. 1 is an isometric view from in front of a paw print accessory incorporating my new design, depicted as a boot; FIG. 2 is a front elevation view of the paw print accessory of FIG. 1;

FIG. 3 is a rear elevation view of the paw print accessory of FIG. 1;

FIG. 4 is a top plan view the paw print accessory of FIG. 1; FIG. 5 is a bottom plan view of the paw print accessory of FIG. 1;

FIG. 6 is a right side view of the paw print accessory of FIG. 1; and,

FIG. 7 is a left side view of the paw print accessory of FIG. 1.

The dashed broken lines in the drawings show unclaimed portions of the paw print accessory, and the dashed-dot broken lines represent boundaries of the design. All the broken lines form no part of the claimed design.
